Primary Examiner — Eric L Goodman*Assistant Examiner* — Sanjeev Paul(74) *Attorney, Agent, or Firm* — Laurence A. Greenberg;
Werner H. Stemmer; Ralph E. Locher(57) **CLAIM**

The ornamental design for a sun protection shield for glasses, as shown and described.

DESCRIPTION

FIG. 1 is a perspective view of the sun protection shield for glasses, showing my new design;

FIG. 2 is a front elevation view thereof;

FIG. 3 is a right side elevation view thereof;

FIG. 4 is a rear elevation view thereof;

FIG. 5 is a left side view thereof;

FIG. 6 is a top plan view thereof;

FIG. 7 is a bottom plan view thereof; and,

FIG. 8 is a perspective view of the sun protection shield for glasses attached to an unclaimed pair of glasses.

The broken lines depict environmental structure of a pair of glasses and do not form a part of the claim.

1 Claim, 8 Drawing Sheets(56)
